United States Patent Office

Des. 193,101
Patented June 26, 1962

193,101

ROBOT SUIT OR SIMILAR ARTICLE

Augustine Del Grosso, 905 S. Main St., Mansfield, Mass.

Filed Feb. 8, 1962, Ser. No. 68,734

Term of patent 14 years

(Cl. D34—15)

Fig. 1.

Fig. 2.

Fig. 3.

Fig. 4.

FIG. 1 is a front elevational view of a robot suit embodying my new design,

FIG. 2 is a rear elevational view thereof,

FIG. 3 is a side elevational view thereof, and

FIG. 4 is a perspective view thereof.

I claim:

The ornamental design for a robot suit or similar article, substantially as shown.
